Des. 207,442
Patented Apr. 18, 1967

207,442

TIGER PAW MITTEN

Lucille T. Facci, 119 Forest Road,
Valley Stream, N.Y. 11581

Filed Aug. 25, 1965, Ser. No. 86,716

Term of patent 3½ years

(Cl. D2—367)

FIG. 1

FIG. 2

FIG. 3

FIG. 1 is an elevational view of the palm side of a mitten showing my new design;

FIG. 2 is an elevational view of the back thereof; and
FIG. 3 is an elevational view of the edge thereof.

I claim:

The ornamental design for a tiger paw mitten, substantially as shown.
